MASSAGER

William G. Betz, La Porte, Ind.

Application November 16, 1938, Serial No. 240,762

4 Claims. (Cl. 128—59)

My invention relates in general to a power driven massaging device, but more in particular to a portable power driven massaging device with flexible fingers individually removable and replaceable on the device, and with such fingers themselves constructed and positioned on the device so that the operation thereof will simulate the most beneficial manual massage.

A lifting, kneading action on the skin is the most efficient and beneficial massage, as such an action tends to stimulate the blood and reach subcutaneous tissues which otherwise are not exercised in a manner which is conducive to a healthy skin. Fatty tissues are reached in this way and are broken down, thus alleviating any necessity for a strenuous reducing diet in order to lose extraneous weight.

Efforts have been made to simulate this action in the prior art massaging devices. However, many of the devices have failed completely to accomplish this end, and others which have been fairly satisfactory from the standpoint of operation, have been so expensive, both in original cost and upkeep that they have had little or no commercial success, and have had very limited distribution. Furthermore, many of the complicated, expensive devices which provide relatively satisfactory massaging require expert care and can be operated successfully only by a person skilled in the use of the particular device.

It is an object of my invention to provide an improved portable, light-weight, compact and sturdy massaging device.

A further object is to provide a portable massaging device which may be operated equally as well by those skilled in the art of massage as by a person with relatively little knowledge thereof.

A further object of my invention is to provide a relatively inexpensive massager which can be adapted to direct motor drive, or indirect drive through a flexible shaft.

Another object of my invention is to provide a simple mechanism requiring little or no servicing and which has inexpensive massaging elements which are readily replaceable when worn out.

One of the features of my invention is the provision of massage elements and driving mechanism whereby a lifting, kneading motion is imparted to the skin to provide the most beneficial treatment. Furthermore, due to the possibility of continuous treatment which remains uniform for any desired period, the use of my device actually provides improved results over that possible with manual finger massage.

Other objects and features of my invention will be apparent from the following detailed description taken with the accompanying drawings wherein:

Fig. 1 is a side view of a portable massaging

unit embodying my invention, driven by an external motor through a flexible shaft.

Fig. 2 is a bottom view thereof showing particularly the massaging fingers.

Fig. 3 is a sectional view along the line 3—3 of Fig. 2 showing the manner in which the massaging members cooperate with each other to lift the skin.

Fig. 4 is an enlarged sectional view along the line 4—4 of Fig. 2 showing one of the driven shafts and massaging fingers carried thereon.

Fig. 5 is a side view of a modification of my invention with the side or end plate thereof removed.

Fig. 6 is a bottom view of a further modification of my invention.

Fig. 7 is a sectional view along the line 7—7 of Fig. 6 as to a portion of the device, and showing other portions in elevation and a massaging element in section.

In practicing my invention, I provide massaging apparatus including a portable frame and a plurality of massaging elements movably supported thereon. Each massaging element includes a frictionally retained bulb-like flexible finger having an annular restricted mouth and a flexible integral cover extending therefrom to provide a compressible end portion at each finger. Each finger is frictionally retained upon a corresponding projection having a shoulder for receiving the annular mouth of the finger behind the same for removably retaining such finger. The projection is mounted on the driven portion of the massaging device and is of such a height, or

length, so far as protruding into the finger is concerned, that the end of the finger can be readily compressed when in operation to provide a relatively soft, yielding structure which will not injure the portion of the body of the person being massaged, yet will knead the skin to reach the subcutaneous tissues and give the maximum stimulation to the portion of the body being massaged. The fingers are retained on such projection so that they will withstand all types of

massaging with the device, and yet can be readily removed for replacement purposes when they become worn.

Referring now to the drawings, Fig. 1 shows a portable massaging device embodying my invention, adapted to be driven by an external motor through the medium of a demountable flexible shaft. This device comprises a one-piece U-shaped frame 10 having a pair of end portions 11 and 12 with a handle 13 rigidly secured to the yoke of the frame and carrying a pair of rotatable shafts 14 and 16 therein. A coupling member 17 (Fig. 2) is rigidly connected to the shaft 14 for connection with a corresponding coupler member on a flexible shaft in accordance with the usual practice. The rotary movement of the

drive shaft 14 is transmitted through a train of gears comprising the gears individually designated by the reference character 18 (Fig. 1), which are enclosed within a removable housing 19 on the end portion 12 of the frame. The shafts 14 and 16 are rotated in opposite directions to carry massaging fingers 21 therewith so that such fingers continuously move on said shafts toward one another to lift the skin to be massaged intermediate the fingers, as shown in Fig. 3. The fingers are preferably provided of a rubber material although it is understood that the invention is not limited to this material if the other characteristics required, as will be apparent, are present.

The shafts 14 and 16 are hexagonal in cross section, and this configuration assists in the spacing of the fingers 21 both longitudinally and angularly of the shafts so that a group of three fingers lies in an arcuate diagonal or substantially helical path extending approximately 180° over the entire periphery of a shaft. This mounting configuration is shown clearly in Figs. 2 and 3. The shafts themselves are spaced apart in the frame a distance such that there is a slight spacing intermediate the substantially cylindrical path of rotation of the outer tip of all of the fingers on one shaft and a corresponding path for the tips of the fingers on the other shaft. This prevents the possibility of jamming the tips of fingers on one shaft against the tips of fingers on the other shaft, should the shafts become angularly displaced from the position illustrated in Figs. 2 and 3, for instance, and also eliminates the possibility of undesirable pinching of skin between the two sets of rollers. Furthermore, with the fingers positioned in the arcuate diagonal line, and the two shafts 14 and 16 angularly positioned with reference to one another so that the sets of fingers on one shaft follow corresponding sets of fingers in timing, there is a progressive lifting and kneading action resulting from the operation of the device which represents the most desirable massaging action.

The desirable massaging action obtained with the structure described above is assisted in providing the most beneficial massage by means of the individual fingers 21 with yielding relatively soft tips which directly engage the skin. Each of the fingers 21 comprises a bulb-like, or hollow-shell-like member having an annular enlarged rim 22 at the mouth thereof and extending outwardly through an integral wall 23 narrower in width than the annular rim 22 to form a compressible yielding tip at the outer end of each finger. The finger is mounted on a projection or knob-like element 24 which may preferably be provided in metal, and is rigidly secured on a shaft 14 or 16 by means of an integral or connected threaded stud 26 fitting in a correspondingly threaded aperture in the shaft. A washer 27 is provided intermediate the shaft and knob as shown on Fig. 4, to seat the finger, close the mouth thereof in cooperation with the knob, and limit the distance which the finger is inserted over such knob. Each knob 24 over the entire massaging device has an enlarged head portion 28 and a restricted neck portion 29 providing a shoulder therebetween to receive the annular rim 22 on a finger thereon. The resiliency of the annular rim 22 is such as to frictionally retain a finger on a knob 24 during a massaging operation, yet make it possible to quite readily remove a worn finger from a knob by pulling more strenuously on the finger than would be repre-

5 sented by the pulling pressure on each finger in a massaging operation. Likewise this resiliency is such that the annular rim 22 can be forced over the rounded face of the head 23 of each knob to mount a finger on a knob.

10 The height of a knob 24 and length of the internal cavity of a finger 21 are such that a considerable portion of the internal cavity of each finger lies above the top of the head 23 of a knob so as to provide an ample yielding mass at the end of each finger for accomplishing the best massaging action.

15 As is clear from Figs. 3 and 4 the knob 24 and consequently the fingers 21 are provided in oppositely disposed pairs as A and B in Figs. 2 and 3. Each pair in turn is angularly displaced from each adjacent pair as is indicated by fingers C and D in Figs. 2 and 3. In other words, the first pair of massage elements on each shaft is angularly displaced and in a different phase relationship than the adjacent pair. This same condition applies to the other adjacent pairs of massage elements over both of the two shafts.

20 In order to project heat directly onto the portion of the body being massaged with all of the beneficial results of such heat, a heating coil 31 is mounted and suitably insulated in a hood 32 supported at the top of the frame 10 and intermediate the two end portions 11 and 12. The current for the heating coil 31 may be provided 25 through a line 33 carried in the handle 13 of the massaging device and connected at one end of the coil as shown in Fig. 2.

25 A modification of the invention is illustrated in Fig. 5 in which a portable massaging device is provided, including a motor 34 carried directly on a frame 36 for direct drive of the massaging elements. A worm gear 34A is mounted on the motor shaft and is in driving engagement with worm gears 37 and 37' mounted at corresponding ends of driven shafts 37A and 37B, respectively. Mounted on the opposite ends of shafts 37A and 37B are worm gears 38A and 38B, respectively, which are operatively associated with gears 39A and 39B, respectively. Gears 39A and 39B are mounted on rotatable shafts 41 and 42, respectively. With the double worm gear units 38A and 39A, and 38B and 39B for the shafts 41 and 42, it is possible to vary the spacing intermediate the shafts 41 and 42 with a minimum of cost and trouble from the standpoint of manufacture. The shafts 41 and 42 are provided in a hexagonal configuration identical with the shafts 14 and 16, in this respect, and the fingers 21 are also provided identical with the fingers illustrated in detail in Figs. 2, 3, and 4, and mounted on the shafts 41 and 42 in a manner identical with that illustrated and previously described. The massaging device can be readily moved over the skin of a patient by means of a handle 43 secured to the motor 34.

30 A further modification of the invention is illustrated in Figs. 6 and 7. In view of the possibility of pulling hair on a patient's head as a result of massaging the head with the structures of Figs. 1 and 5, due to rotation of the shafts and fingers thereon toward one another, a rotatable head 46 is provided in the structure of Figs. 6 and 7 which is driven through a substantially reciprocating link 47 pivotally secured to a disc 48 at one end and to a disc 49 at the other end. The disc 49 is rotated through 360° through a driving connection including a stub shaft 51 and a coupler portion 52 for connection

with an external, flexible driving shaft in the same manner as described with reference to the structure in Figs. 1 to 4, inclusive. As is apparent from both Figs. 6 and 7, the disc 49 is smaller than the disc 48. The link 47 is pivotally secured adjacent the periphery of each disc. The ratio between the diameters of the discs 49 and 48 is such that while the disc 49 rotates completely through 360°, the disc 48 rotates in one direction through approximately 180° and then in the opposite direction through the same circular path. As a result of this motion, the fingers 21' secured to the head 46 act through the hair of the patient and directly onto the scalp in a massaging motion very similar to that normally practiced in a manual massage of the head, causing the scalp to be moved sufficiently to loosen and stimulate the same without in any way pulling the hairs or causing discomfort to the patient.

In order to more readily accommodate a plurality of fingers on the circular head 46, these fingers are provided in a substantially conical form as is apparent in Fig. 7. Each finger, and the fingers are preferably provided in a rubber material as mentioned above, comprises an annular rim 22' and an integral compressible cover at a tip portion 23'. Each finger is frictionally and removably secured to a knob 24' similar to the knob 24 of Fig. 4 having a head portion 28' and a restricted neck portion 29' for carrying a finger thereon in a clincher-like manner as previously described.

The stub shaft 51 for the disc 49 and a similar shaft 53 for the disc 48 are each journalled in a frame plate 54 acting with a frame member 56 and frame plate 57 to provide a closed housing for the link 47 and associated movable mechanism. The housing is long and relatively narrow, and of such a size as to be comfortably grasped in the hand of an operator to serve as the operating handle for the complete massaging device. It is understood that a motor member, if desired, can be directly connected to the shaft as 51 to drive the massaging device in a manner similar to the drive for the structure of Fig. 5.

Although I have described my invention in its preferred embodiments, it is understood that the invention is not to be limited thereby but changes and modifications may be made therein all within the scope of the appended claims.

I claim:

1. A massage device for carrying in the hand for body massage and the like including in combination a pair of spaced-apart rotatable shafts, a plurality of massage elements on each shaft positioned thereon in pairs and each element in a pair being substantially oppositely disposed with respect to the other element, with each pair of massage elements axially disposed on said shaft with reference to the next adjacent pair and in a different phase relationship on said shaft relative to said adjacent pair, means on each of said shafts for individually supporting said massage elements thereon and positioned on each shaft to provide said massage element pairs in said different phase relation, frame means supporting said shafts radially displaced from one another a distance such that the circumferential path followed by the outer tips of the massage elements on one shaft does not cut the circumferential path followed by the outer tips of the massage elements on the other shaft, a motor

5 mounted on said frame means having a shaft arranged intermediate said two shafts, with the axes of said motor shaft and said two shafts being in a parallel relation, individual driving means for each of said two shafts including an elongated driven member operatively connected at one end to the corresponding shaft, and gear means on said motor shaft operatively connected to each of said driven members at the other end thereof to simultaneously drive both said driven members to drive said two massage element shafts in opposite directions.

2. A power-actuated massaging device for carrying in the hand for body massage and the like, including in combination a pair of spaced apart rotatable shafts, frame means for supporting said shafts, each of said shafts having a plurality of massaging elements securely but removably carried thereon, means carrying said massage elements on said shafts including a plurality of projections on said shafts extending radially from the shafts and arranged in pairs substantially over the axial length of said shaft, with the projections in each pair being substantially oppositely disposed on said shaft, said carrying means for each of the massage elements including a threaded portion and each of said shafts having a corresponding threaded opening for threadably receiving said threaded portion, with each of said massage elements having a hollow interior fitting over a corresponding projection and held releasably thereon.

3. A massaging device for carrying in the hand for body massage and the like, including in combination a pair of spaced apart rotatable shafts, frame means for supporting said shafts, a plurality of massaging elements individually carried on said shafts, with each of said shafts having threaded apertures extending radially therethrough, said apertures being axially spaced with adjacent ones thereof being in an angularly displaced relation, and a supporting member for each of said massaging elements, said supporting member having a head portion and a threaded shank portion, with said head portion being adapted to retain a corresponding massaging element thereon, and said shank portion being threadable in the end of an aperture.

4. A massaging device for carrying in the hand for body massage and the like including in combination a pair of spaced apart rotatable shafts, each of said shafts having a plurality of flat sides oppositely arranged in pairs, and axially spaced threaded apertures extending radially therethrough, with said apertures being relatively angularly spaced so that adjacent ones thereof correspond to a different pair of shaft sides, frame means for supporting said shafts, each of said shafts having a plurality of substantially hollow massaging elements securely but removably carried thereon, and a carrying unit for each of said massaging elements, said carrying unit having a head portion, a threaded shank portion, and an intermediate engaging portion, with said threaded portion being threadable in the end of one of said apertures until said engaging portion frictionally engages the shaft side corresponding to said aperture end, the threaded portions at opposite ends of a corresponding aperture being spaced apart axially of said corresponding aperture, and each of said hollow massaging elements fitting over a corresponding head portion to be releasably held thereon.

WILLIAM G. BETZ.
